G. RICHTER.

METHOD AND APPARATUS FOR ANNEALING OR CEMENTING VARIOUS ARTICLES.

APPLICATION FILED MAY 29, 1913.

1,109,362.

Patented Sept. 1, 1914.

UNITED STATES PATENT OFFICE.

GEORG RICHTER, OF STETTIN, GERMANY, ASSIGNOR TO STETTINER CHAMOTTE-FABRIK AKTIEN-GESELLSCHAFT VORMALS DIDIER, OF STETTIN, GERMANY, A CORPORATION OF GERMANY.

METHOD AND APPARATUS FOR ANNEALING OR CEMENTING VARIOUS ARTICLES.

1,109,362.

Specification of Letters Patent. Patented Sept. 1, 1914.

Application filed May 29, 1913. Serial No. 770,568.

To all whom it may concern:

Be it known that I, GEORG RICHTER, a subject of the German Emperor, and a resident of Stettin, Germany, have invented certain new and useful Improvements in Methods and Apparatus for Annealing or Cementing Various Articles, of which the following is a specification.

My invention relates to an improved heat-treatment and to apparatus for conducting such treatment, as in annealing or cementing various articles, for instance malleable castings.

According to my present invention, the articles to be treated are caused to travel continuously and while thus in motion they are subjected successively to the action of heating gases and of cooling gases, both of which are arranged to travel transversely of the direction in which the articles are proceeding, the transverse gas-currents flowing alternately in opposite directions.

An apparatus suitable for carrying out my new process is constructed with a passage or tunnel through which the articles to be treated are caused to travel lengthwise, said apparatus or furnace being subdivided into a number of compartments or zones through which the heating agent and the cooling agent are conducted alternately in opposite directions as the articles travel through the furnace.

The advantages of my improved process and apparatus consist in the fact that the operation is continuous and furthermore in the securing of a practically uniform heating and cooling effect respectively in the successive portions or zones of the furnace.

A specific example of a furnace constructed according to my invention will now be described with reference to the accompanying drawings, and the novel features of the improved process and apparatus will then be pointed out in the appended claims.

Figure 1 is a horizontal section of the furnace, taken on the line A—B of Fig. 2; Fig. 2 is a cross section on the line C—D of Fig. 1; Fig. 3 is a partial longitudinal section taken on the line E—F of Fig. 2; and Fig. 4 is a cross section on the line G—H of Fig. 1.

The articles or material to be subjected to the treatment (annealing or cementation) are put in cylindrical boxes or receptacles 1 standing on cars or trucks 4 arranged to

travel on rails 3 extending at the bottom of the longitudinal passage 2 of the furnace. In the example shown, each truck carries four receptacles 1 and is provided with a longitudinal partition 6 extending between the two rows of receptacles and perforated at its lower portion, as indicated at 5. The receptacles or cans 1 are in close contact with the partitions 6 and come very close to the side walls of the passage 2. Each two trucks constitute a carriage unit. On two receptacles 1 located at one end of a carriage unit is placed an arched member 7 constructed of refractory material and extending almost into contact with the side walls of the passage 2 and with its roof 8, which is of uniform height and shape throughout the length of the furnace. The arched members 7 travel with the trucks 4 and divide the interior of the passage 2 into a number of successive zones or compartments designated by the reference characters I, II, III, to IX inclusive, each zone being approximately co-extensive with one carriage unit.

At each side the furnace is provided with combustion chambers 9 and 10 respectively, as well as with channels 11, 12, 13, and 14 for the combustion gases and with channels 15, 16, 17, and 18 for the cooling agent (cool air). As shown in Fig. 1, the combustion chamber 9 and the connecting channels 11, 12, 17 and 18 on one side of the furnace are out of transverse alignment with the combustion chamber 10 and with the connecting channels 13, 14, 15, and 16 respectively on the other side of the furnace. The channels 11, 12, 13, and 14 serving to convey the combustion gases communicate with the passage 2 by means of openings 19, and similarly, openings 20 lead into the passage 2 from the channels 15, 16, 17, and 18 serving to convey the cooling air. With the combustion chamber 10 is connected a channel 21, arranged opposite the combustion chamber 9. The latter communicates with the passage 2 by means of openings 22, while the combustion chamber 10 and the channel 21 are connected with the said passage 2 by openings 23.

The channels or channel sections 11, 12 are separated by a partition or baffle 36, a similar baffle 36^a separates the channel section 13 from the channel section 14, and in a like manner, there is a baffle 36^b between the

channel sections 15 and 16, and another baffle 36^c between the channel sections 17 and 18. Baffles 37, 37' separate the combustion chamber 9 from the channel sections 11 and 18 respectively, and baffles 38, 38' separate the channel 21 from the channel sections 13, 16 respectively. The baffles are arranged out of transverse alinement, or in staggered fashion on opposite sides of the passage 2, and the distance between successive baffles is about equal to the length of one of the zones I, II, etc., or in other words, to the distance between two adjacent arched members 7. As more fully set forth hereinafter, these various channel sections, baffles and arched members compel the hot gases and the air to travel in the zig-zag paths indicated, crossing the longitudinal passage 2 repeatedly in opposite directions. It will be understood that the channel sections on opposite sides of the central passage 2 communicate with each other through portions of said passage.

All the openings 19, 20, 22, and 23 communicate with the passage 2 at a level immediately above the carrying platform of the trucks 4. The cooling air channel 15 is connected with the surrounding air at one end, as at 24. The cooling air channels 18 and 16 are connected with the combustion chambers 9 and 10 respectively, by channels 27, 28 and 25, 26 respectively. The channels 26, 28 convey primary air to the ash-pits under the grates 30, 29, while a secondary supply of air is conveyed by the channels 25, 27 to the combustion chambers 10 and 9 respectively, above their grates. The excess of cooling air is carried away through channels 31, 32 (Fig. 4) connected with the channels 16 and 18, and if desired, regulating slides or dampers (not shown) may be provided in these channels. The spent combustion gases or waste gases escape from the channel 14 by way of a smoke flue 33 connected with the stack 34. At each end of the passage 2 I provide slides 35 made of sheet-metal or other suitable material, for the purpose of closing said ends.

My improved process is carried out as follows by means of the furnace described above: The trucks 4 carrying the receptacles 1 with the material or articles to be annealed or cemented, are caused to travel through the furnace stepwise in one direction (from right to left in Fig. 1), the operation of the furnace being continuous; the material or articles to be treated will thus first reach zone I, then they will be advanced to zone II, after staying there for a suitable length of time, they will be transferred to zone III, and so on from zone to zone until zone IX is reached. The combustion gases coming from the grates 29 of the combustion chamber 9 reach the passage 2 through the openings 22, stream across

said passage in zone V, and thus strongly heat the material or articles contained within that zone. The gases then travel through the openings 23 and the channel 21 to the other combustion chamber 10 and become mixed with the combustion products rising from the grates 30 of said combustion chamber 10. The gases then pass through the openings 23 into the passage 2 and cross the latter in zone IV, in the direction opposite to their path through the zone V; the material or articles contained in zone IV are thus subjected to a high degree of heat. Thereupon the combustion gases pass into the channel 11 through the openings 19 at the left-hand end of said channel, and from the right-hand end of the channel 11 the gases reach the passage 2 through the openings 19 at that end, crossing the zone III in the direction opposite to the flow of the gases in zone IV. In a similar way the combustion gases are passed successively through the zones II and I, with the aid of the channels 13 and 12, and finally the waste gases escape to the stack 34 through the channel or flue 33, connected with the channel 14. During the passage of the combustion gases through the zones III, II, and I the temperature of said gases sinks gradually, so that the material in the receptacles 1 is subjected to a progressively increasing heat as it passes from the entrance (right-hand end in Fig. 1) to the central portion of the furnace. The cooling air enters the channel 15 through the opening 24 and then reaches the passage 2 through the openings 20, whereupon it streams across the passage 2 in zone IX, to then travel successively in opposite directions through the zones VIII and VII, by way of the channels 17 and 16. As it passes successively through the zones IX, VIII, and VII, the cooling air is heated progressively, while the material or articles in the receptacles 1 are cooled more and more, gradually but in a progressively increasing degree, as they travel from the central portion of the furnace to its outlet (at the left-hand end in Fig. 1). A portion of the air thus heated continues to travel to the right in the channel 16 and passes to the combustion chamber 10, through the channels 25 and 26, to support combustion in said chamber. Similarly, a portion of the heated air which has reached the channel 18 after streaming across zone VII, is led through the channels 27, 28 to support combustion in the chamber 9. The excess of air will escape from the channels 16, 18 through the channels 31 and 32 (Fig. 4). In my improved furnace described above the combustion gases and the cooling air pass through the several zones of the passage 2 in their entire breadth, and I thus avoid the formation of "dead" spaces in which the heating or cooling gases might

become trapped and therefore ineffective. A portion of the heating or cooling agent will pass immediately above the carrying platform of the trucks 4, through the openings 5 of the longitudinal partitions 6, while another portion of said agents will flow over the partitions 6, as indicated in Fig. 2.

Various modifications may be made without departing from the nature of my invention as set forth in the appended claims.

I claim as my invention:

1. The herein described process for annealing or cementing articles or material, which consists in causing the said articles to travel in a predetermined direction and subjecting them successively to the action of heating currents and of cooling currents conducted transversely of the first-mentioned direction and alternately in opposite directions.

2. The herein described process for annealing or cementing articles or material, which consists in causing the said articles to enter a furnace successively and to travel therethrough in a predetermined direction, and causing currents of a heating agent and of a cooling agent respectively to flow alternately in opposite directions through successive portions or zones of said furnace, transversely to the path of the articles undergoing treatment, so as to secure a uniform heating and cooling of said articles in the successive furnace zones.

3. The herein described process for annealing or cementing articles or material, which consists in subjecting a consecutively arranged series of such articles to the action of heating and cooling currents flowing transversely of the series at different zones thereof, and advancing said series stepwise so as to bring its several portions successively into the several heating and cooling zones, the articles being advanced transversely of the path of said currents.

4. An annealing or cementing furnace provided with a longitudinal passage, combustion chambers located at opposite sides of said passage, out of transverse alignment, and channels located in the side walls of the furnace and communicating with said chambers, the channels on each side of the passage being divided into separate sections, and the channel sections on opposite sides of said passage being connected with each other by successive portions of said passage so as to compel the gases from said chambers to travel in a single current or stream across the full width of said passage alternately in opposite directions through successive portions or zones of said passage.

5. An annealing or cementing furnace provided with a passage extending therethrough lengthwise, combustion chambers

located at the central portion of the furnace on opposite sides thereof, longitudinal channel sections located adjacent to said passage and communicating therewith and also with said combustion chambers, baffles located in staggered arrangement on opposite sides of said passage and separating adjacent channel sections, an air inlet at one end of the furnace, an outlet for combustion gases, at the other end of the furnace, and means to cause the cooling air to travel from one end of the furnace to the combustion chambers, and the combustion products to travel from said chambers to the other end of the furnace, the stream of cooling air and the stream of combustion products passing repeatedly across the entire width of said passage, alternately in opposite directions.

6. An annealing or cementing furnace provided with a passage extending therethrough lengthwise, combustion chambers located at opposite sides of said passage, channel sections extending along the side walls of said passage and communicating therewith and also with said combustion chambers, and partitions separating adjacent channel sections and compelling the currents flowing therein to cross said passage in its entire width in order to get from a channel section on one side of the passage to a channel section on the opposite side of said passage.

7. An annealing or cementing furnace provided with a longitudinal passage, trucks adapted to carry the material or articles to be treated and arranged to travel lengthwise of said passage, channels for causing a current of the treating medium to flow across said passage at different points thereof, and longitudinal partitions arranged at the central portions of said trucks and terminating short of the furnace roof so that a portion of the treating current will flow over said partitions, the latter being provided with openings at their lower portions to allow another portion of the treating current to pass in a direct path from one side of the furnace to the other.

8. A furnace provided with a longitudinal passage for the material to be treated, longitudinal channel sections adjacent to said passage, communicating therewith, and baffles separating adjacent channel sections and arranged in staggered fashion on opposite sides of said passage.

In testimony whereof, I have signed this specification in the presence of two subscribing witnesses.

GEORG RICHTER.
